UNITED STATES PATENT OFFICE

1,983,659

METHOD FOR HANDLING RESIDUUM

John Cutter, Tulsa, Okla., assignor, by mesne assignments, to Universal Oil Products Company, Chicago, Ill., a corporation of South Dakota

Application March 19, 1927, Serial No. 176,589
Renewed June 21, 1933

4 Claims. (Cl. 196—1)

This invention relates to a method for handling residuum and has special reference to a method for handling residuum from stills or reaction chambers, vaporizing drums or any other receptacle connected thereto.

More particularly, this invention relates to a method for removing residual oils or any heavy petroleum derivatives from any part of petroleum distillation apparatus which in the course of operation becomes clogged with coke and saturated with the above mentioned derivatives. Also, this invention relates to a method for removing and condensing any obnoxious vapors arising from said residual oil or said petroleum derivatives when removed from said distillation apparatus.

In the handling of residuum, it is particularly objectionable to permit the vapors therefrom to escape directly into the atmosphere for the reason, among others, that these vapors deposit a resinous-like compound on the surrounding objects. Further, a considerable amount of saleable oil may be recovered from these vapors, and as this saleable oil is of a quality which may be used as a charging stock, a monetary gain is derived aside from the suppression of the obnoxious vapors. Furthermore, by locating this apparatus as close as possible to the distillation equipment and making all connecting lines as direct as possible, thus reducing pipe line friction to a minimum, this method and apparatus permits the residual oil in the still, or other apparatus, to be withdrawn rapidly, leaving the coke deposit in such still free from any liquid or asphaltic compound which produces a better quality of coke and also makes the coke much easier to remove from the still.

One of the objects of this invention is to provide a new and novel method for handling residuum.

A further object of this invention is to provide a method for removing residual oil or any heavy petroleum derivatives from any part of petroleum distillation apparatus.

A further object of this invention is to provide a method as indicated above which will prevent the escape of objectionable vapors from the residual oils withdrawn from distillation apparatus.

A further object of this invention is to provide a method of the above mentioned type capable of recovering saleable oil from the vapors given off from residual oils.

A further object of this invention is to provide a method as hereinbefore mentioned which will serve as a cooling medium to harden the asphaltic

compound of residual oils into such a condition that it may be handled readily.

A further object of this invention is to provide a method of the character hereinbefore outlined, which will permit of the rapid withdrawal of residual oils from stills or other distillation apparatus whereby a better quality of coke is obtained and the same is more readily removed.

Further objects and advantages will be apparent from the description and drawings forming a part of this specification to which reference may now be had for a more complete understanding of the characteristic features of this invention, in which drawings:

Figure 1 is a diagrammatic view of the present invention as associated with an apparatus for treating petroleum;

Fig. 2 is a front elevational view partially in section of the apparatus of this invention;

Fig. 3 is a top plan view of Fig. 2; and

Fig. 4 is a detail of the liquid seal, the same being a vertical section thereof.

Obviously, the process and apparatus of this invention can be utilized with any apparatus in which a carbon residuum is formed and, therefore, the drawings and following description show merely in skeletonized form a standard oil cracking system.

Referring to the drawings, and more particularly to Figure 1, it will be evident to those skilled in the art that the cracking system shown is an apparatus of the tube and tank type comprising the reflux tower 11, the still 12, the vaporizing chamber 13, a condenser 14, and distillate receiver 15.

This apparatus is all shown in conventional form as the construction thereof is well known to those skilled in the art. Briefly, the operation of such a still is as follows:

The oil is admitted to the reflux tower through the pipe 10, from which it is drawn by the pipe 16 into the cracking tubes 17 of the heating chamber of the still 12, from where the oil is forced into the vaporizing chamber 13, and from which the vapors are carried to the reflux tower by the pipe 18. The vapors which are not refluxed are withdrawn from the top of the reflux tower to the condenser 14 where they are condensed and the uncondensable gas and cracked distillate are then collected in the distillate receiver 15. The residuum which contains the carbon generated in the cracking operation collects in the vaporizing chamber 13.

This invention relates to the handling and treatment of this residuum and the foregoing description of the cracking apparatus and process is illustrative merely, as any other process in which a carbon residuum is generated can be substituted therefor.

The residual oil in the vaporizing chamber is drawn off through blow-down line 19 at a pressure ranging from a few pounds per square inch 10 to approximately 800 pounds per square inch. This blow-down line 19 is connected to the bottom of a basin 20. Prior to the withdrawal of the substance from the vaporizing chamber 13, a drum 21 having no bottom, mounted by means 15 of a chain hoist 22 to the drum supports 23, is lowered to within a few inches of the bottom of the concrete basin 20 and centrally of the outlet of the line 19. The basin, which is approximately 50 feet square, is then partially filled 20 with water to a depth of substantially 16 inches thus forming a water seal of a depth of 12 inches or more around the drum. These dimensions, of course, may be altered according to the sizes 25 of the various apparatus and are mentioned here only for the purpose of clearer explanation.

Hot residual oil may then be discharged from the evaporating chamber 13 by means of the blow-down line 19 into the basin and upon entering the drum 21 at atmospheric pressure, said 30 oil is partially vaporized and the volatile portion is carried off through the conduit 24, liquid seal 25, conduit 24^a, and condensed in the condenser coils 26. The liquid, thus condensed, then flows to a sump through the line 27. The heavy 35 asphaltic product contained in the residual oil is forced out of the drum 21, past the water seal formed by the bottom of the drum, and is spread over the surface of the basin 20. The water in the basin then serves as a cooling medium to 40 harden the asphaltic compound into such a condition that it may be readily handled, that is, shovelled into trucks or other conveyances.

Referring more particularly to Figs. 2 and 4, it will be noted that the connection between the 45 drum and the stationary conduit 24^a is so constructed as to permit of the raising and lowering of the drum at the will of the attendants, eliminating the necessity of manually controlling the vapor line before the position of the drum is 50 changed. This construction comprises a tubular stem portion 28, which is stationary and communicates with the conduit 24^a, a sleeve member 29, disposed around the stem 28 and connected to the conduit 24, and a jacket 30 which is stationary with the stem 29 and encompasses both 55 the stem and the sleeve portions. The jacket is provided with water through an inlet 31 which inlet is disposed just below the top of the stem portion 28 and as there is no relative movement 60 between the stem and jacket portions 28 and 30, respectively, this water level will remain unchanged. It will be apparent that a liquid seal will be maintained through the vapor line regardless of the particular position of the drum and 65 no vapors will be permitted to escape. Also, this condition is provided automatically and requires no manual control.

Referring again to Fig. 1, it will be noted that 70 the blow-down line 19 permits of the free removal of the residual oils from the evaporating chamber 13, which condition is due largely to the minimizing of pipe line friction by making all connecting lines as short and direct as possible. This rapid withdrawal of the residual oil from 75 the chamber leaves the coke deposit therein free

from any liquid or asphaltic compound and may be removed through the manhole 32. This construction produces a much better quality of coke and makes the coke much easier to remove from the still.

As a result of this invention, a new and novel method of handling residuum from petroleum distillation apparatus is provided in which a valuable oil is recovered from vapors, which, if permitted to escape directly into the air, would be 10 obnoxious in many ways. Also, an apparatus is provided whereby a better quality of coke is obtained from distillation apparatus and said coke is more readily removed from said distillation apparatus. Still further, this invention provides 15 an apparatus whereby the asphaltic compound of the residual oils of distillation apparatus is cooled and thereby solidified, which condition permits of the same being handled very conveniently.

While a single embodiment of this invention is herein shown and described, it is to be understood that the device is not to be limited to that specific structure since various modifications may be apparent to those skilled in the art without departing from the spirit and scope of this invention, and therefore, the same is to be limited only by the scope of the appended claims and the prior art.

I claim:

1. A method of handling unvaporized residual oil obtained in the heat and pressure cracking of hydrocarbon oils and containing volatile portions and heavy asphaltic products which comprises removing such residual oil from the cracking process under superatmospheric pressure, introducing said residual oil while at elevated temperature into a vaporizing zone below the level of a body of water maintained in the lower portion of said zone, lowering the pressure on the residual oil in said zone sufficiently to vaporize the volatile portions of the residual oil by the self-contained heat of the latter, effecting substantial solidification of the heavy asphaltic products of the residual oil by contact with the water in said zone, and separately removing the vaporized volatile portions and the unvaporized asphaltic products from said zone.

2. A method of handling unvaporized residual oil obtained in the heat and pressure cracking of hydrocarbon oils and containing volatile portions and heavy asphaltic products which comprises removing such residual oil from the cracking process under superatmospheric pressure, introducing said residual oil while at elevated temperature into a vaporizing zone below the level of a body of cooling liquid other than the residual oil and maintained in the lower portion of said zone, lowering the pressure on the residual oil in said zone sufficiently to vaporize the volatile portions of the residual oil by the self-contained heat of the latter, effecting substantial solidification of the heavy asphaltic products of the residual oil by contact with the cooling liquid in said zone and separately removing the vaporized volatile portions and the unvaporized asphaltic products from said zone.

3. A method of handling unvaporized residual oil obtained in the heat and pressure cracking of hydrocarbon oils and containing volatile portions and heavy asphaltic products which comprises removing such residual oil from a cracking zone under superatmospheric pressure and introducing the same while at elevated temperature into a vaporizing zone, contacting the entire por-

tion of the residual oil so removed from the cracking zone, with a cooling liquid other than the residual oil, lowering the pressure on the residual oil while in transit from the cracking zone to the

5 vaporizing zone sufficiently to vaporize the volatile portions of the residual oil by the self-contained heat of the latter, effecting substantial solidification in said vaporizing zone of the heavy

asphaltic products of the residual oil contacted with the cooling liquid, and separately removing the vaporized volatile portions and the solidified products from said zone.

4. The method as defined in claim 3 further characterized in that said cooling liquid comprises water.

5

JOHN CUTTER.
